UNITED STATES PATENT OFFICE.

JOHN B. DAVIDS, OF NEW ROCHELLE, NEW YORK.

INK STAND OR RECEIVER.

SPECIFICATION forming part of Letters Patent No. 295,739, dated March 25, 1884.

Application filed January 7, 1884. (No model.)

To all whom it may concern:

Be it known that I, JOHN B. DAVIDS, a citizen of the United States, residing at New Rochelle, in the county of Westchester and State of New York, doing business in the city, county, and State of New York, have invented an improved device particularly adaptable to Ink-receivers, of which the following is a specification.

10 My invention relates to an improved device adapted to be applied to ink-bottles, so as to enable them to be used as inkstands.

The accompanying drawings illustrate the best means of carrying out my invention.

15 Figure 1 is a front view of a bottle with my improved belt or band applied thereto, with the parts in position for transportation. Fig. 2 is a similar front view with the parts in position for use as a rack or holder. Fig. 3 is a 20 plan view of Fig. 2.

Similar letters of reference indicate like parts wherever they occur.

Referring to the drawings, A represents an ink bottle or receiver of an ordinary or suitable construction, around which is arranged a metallic or other suitable band, B, which is cut, stamped, or otherwise formed so that portions b may, when desired, be turned or bent out, so as to form rests or holders for pens, 25 pencils, or other instruments or articles. The main body of the band, as well as the portions adapted to be turned out, may be embossed, stamped, lacquered, printed, painted, or otherwise ornamented or provided with designating or advertising matter or devices.

In Fig. 1 I have shown a bottle with my improved device applied thereto, with the parts lying flat against the surface of the bottle.

40 In Figs. 2 and 3 I have shown the parts b turned or bent out into position to hold a pen-

holder, pencil, or other article usually employed by a writer.

In the drawings I have shown two sets of racks or holders formed by stamping or cutting four portions, b, from the main ring B. I can, however, with equal facility, stamp or cut any other number of portions b and turn them out, when desired, so as to form racks or holders. In all cases I prefer that the parts b be stamped or cut in radial lines, so that when the said parts are turned out to form racks or holders the upper surfaces of each pair or series of the said racks or holders shall be in a parallel line.

By means of my invention I am enabled to present to the public a useful inkstand or ink-receiver at very small cost, while at the same time the said inkstand is capable of being employed as a holder for pens and other articles, 55 and also as an advertising medium.

I prefer to form the band of metal either plated, coated, or otherwise decorated; but it may with equal facility be formed of any other material which would allow of the parts 60 b being turned out in the manner described.

Having thus described my invention, what I claim, and desire to secure by Letters Patent, is—

As an article of manufacture, a bottle or receiver provided with a belt or band having divisions or sections capable of being distended or turned out into position to form racks or supports for pen-holders, pencils, and other similar instruments, substantially as shown 75 and described.

In witness whereof I have hereunto set my hand,

JOHN B. DAVIDS.
